HOMER S. ROGERS, OF MILWAUKEE, WISCONSIN, ASSIGNOR TO MILWAUKEE AIR POWER PUMP COMPANY, OF MILWAUKEE, WISCONSIN, A CORPORATION OF WISCONSIN

PNEUMATIC PUMP

Application filed May 17, 1926. Serial No. 109,549.

This invention relates to improvements in thereof and being provided with the water single cylinder pneumatic pumps of the type intake port 12 controlled by a suitable check more particularly adapted for pumping water from wells.

One of the objects of the present invention is to provide an improved pump of the character referred to wherein the actuating mechanism for the fluid exhaust and inlet valves functions to cause simultaneous opening and closing of the same, respectively, as shown to open with the pressure in the pumping chamber 14. For the purpose of controlling the admission of fluid into the pumping chamber 14 when the water in the pumping chamber reaches the low level point and irrespective of the rate at which water may be drawn from the pumping chamber at the instant the low level point is reached, this mechanism providing for such operation of these valves in a quick positive manner.

Another object is to provide an improved pump of the character referred to wherein the actuating means for the fluid exhaust valve includes a member acting as a float at high level to cause closing of this valve and acting at low level to urge the valve away from its seat, and wherein means are arranged in the pumping chamber responsive to low level conditions therein to act upon the exhaust valve at this time and initiate opening movement thereof while permitting continuation and completion of this movement by the above member which at this time is above the water level and acts as a weight.

Another object is to provide an improved pump of the character referred to wherein the actuating mechanism for the fluid inlet and exhaust valves is simple in construction and operation and is capable of operating continuously over a relatively long period of time without replacement or readjustment of any of the parts.

Other objects and advantages will hereinafter appear.

For the purpose of illustrating the invention one embodiment thereof is shown in the drawing, wherein

Figure 1 is a vertical sectional view of the pump; and

Fig. 2 is a horizontal sectional view, taken on the line 2-2 of Fig. 1.

The pump casing comprises the cylinder

member 15 closing the upper end of cylinder 10 and being provided with the fluid inlet passage 16, the fluid outlet or exhaust passage 17, and the water outlet passage 18 controlled by a suitable check valve 19 arranged

as shown to open with the pressure in the pumping chamber 14. For the purpose of conveying water from the pumping chamber 14 to the water outlet passage 18, a pipe 20 is threaded into the underside of head portion 15 and extends downwardly to within a relatively short distance from the bottom of the pumping chamber.

For the purpose of controlling the fluid outlet or exhaust passage 17, a suitable valve 21 is provided and arranged to close with the pressure in pumping chamber 14, as shown, a suitable needle valve 22 being provided to control the admission of fluid under pressure from passage 16 to the pumping chamber and being arranged to close against the pressure in passage 16.

A lever arm 23 is pivotally connected intermediate its ends at 24 to a depending lug 25 which may be formed integrally with member 15. Member 23 is pivotally connected at one end thereof to the fluid inlet valve 22 by means of a link 26 and is pivotally connected at the point 27 to the fluid exhaust valve 21, this member thus providing for simultaneous opening and closing of the fluid exhaust and inlet valves, respectively, as well as simultaneous reverse movement of these valves. The other end of member 23 is provided with a transverse head or cross-piece 28. A float 29 is fixed to the underside of lever 23 below the fluid exhaust valve 21, and acts at high level conditions in the pumping chamber to close exhaust valve 21 and open the fluid inlet valve 22, the arrangement being such that valve 22 is fully open just before exhaust valve 21 seats whereby the closing movement of the latter is completed by the air pressure acting thereon. While float 29 acts in this manner when the water in chamber 14 reaches

the line 2-2 of Fig. 1.

the high level point, it is proportioned so as to have an appreciable weight under low level condition in the pumping chamber when it is not subject to the buoyant action 5 of the water. The relation between the area of the fluid exhaust valve 21 and the weight of float 29, however, is such that when the parts are in their respective positions, as shown in Fig. 1, at which time the fluid inlet 10 valve 22 is open and pumping chamber 14 is under the working pressure, the force acting upwardly upon the underside of valve 21 is sufficient to sustain the weight of float 29 and to hold this valve closed against the 15 weight of member 29 tending to pull the same from its seat. It will thus be apparent that some means must be provided for initiating or starting the opening movement of the fluid exhaust valve 21 when the water 20 in chamber 14 reaches the low level point, and to this end a lever 30 is pivotally connected at one end thereof by means of a pin 31 to a lug 32 which may be formed integrally with head member 15, the other end 25 of this lever being pivotally connected at 33 to a vertically arranged rod 34 having a float or buoyant member 35 fixed to the lower end thereof. The portion 38 of lever 30 is bent outwardly around valve 21 and pipe 20, as 30 more clearly shown in Fig. 2, and a similarly shaped complementary piece 39 is secured at its ends to lever 30 by means of pin 31 and a rivet or other suitable means 40. As shown in the drawing, lever 30 is arranged upon 35 downward pivotal movement thereof to engage head 28 of member 23, a slight amount of loose play being provided between these parts when the same are in their respective positions as shown in Fig. 1.

40 Member 35 is sufficiently buoyant to cause upward pivotal movement of lever 30 to the position shown upon filling of the pumping chamber 14 through valve 13. The arrangement and weight of member 35 is such that 45 when the level of the water in chamber 14 drops to a point slightly short of the lower end of the water outlet pipe or passage 20, the effective weight of member 35 will then be sufficient to cause downward pivotal movement of lever 30 about pin 31 as a center whereby lever 30, upon engagement thereof with head 28 at the outer end of member 23, initiates downward movement of the latter against the pressure in chamber 14 acting to 50 hold the fluid exhaust valve 21 against its seat. The instant valve 21 is started from its seat the weight of member 29 will act to continue and complete the opening movement of valve 21 as well as the accompanying 55 closing movement of the fluid inlet valve 22, this movement taking place at a relatively rapid rate after valve 21 has once been started from its seat. It is to be noted that when once the fluid exhaust valve 21 is started from its seat the weight of float 29 will be

sufficient to continue and complete the opening movement of valve 21 and the closing of inlet valve 22 although the drawing of water from the pumping chamber may be stopped or continued at a very slow rate at this instant. Water will then flow into the pumping chamber by way of valve 13 and fill chamber 14 until float 29 is lifted to close valve 21 and open valve 22, thus completing the cycle. There is, therefore, no "dead center" position of the actuating mechanism for the fluid exhaust and inlet valves 21 and 22. 70 It might be found advantageous, under certain conditions, to supplement or augment the action of the low level float 35 in causing opening of the fluid exhaust valve 21 in the manner explained, and to this end a relief valve of any suitable construction, designated generally by reference numeral 36, may be arranged below the low water line in the pump chamber for engagement by float 35, as shown, to provide an auxiliary water outlet in the pump chamber at substantially the same instant at which this float begins to function to open valve 21. The arrangement 80 is such that the relief valve 36 begins to open under the weight of float 35 just before lever 30 engages the head 28 of lever 23, at which time this opening of valve 36 causes an appreciable drop in the water level 85 which otherwise would not occur whereby the buoyant action of the water on float 35 is correspondingly decreased to make effective a greater proportion of the weight of float 35 in effecting downward pivotal movement of lever 30 to open valve 21 against the working pressure in the pump chamber. Relief valve 36 in this manner provides for more rapid actuation of the fluid valves at low level condition in chamber 14, and also permits of a decrease in the size of float 35 for efficient operation of the pump. In the drawing valve 36 is shown as comprising a pin 37 threaded into foot member 11 and provided with an axial passage 38 opening at its lower end and communicating with the interior of chamber 14, a sleeve or valve member 39 having a sliding fit over pin 37 and provided with an opening 40 arranged to register upon downward movement of the sleeve with the upper end of passage 38, and a spring 41 arranged on pin 37 between member 11 and the lower end of sleeve 39 for urging the latter upwardly to valve-closing position, a pin or stop 42 being provided at the upper end of pin 37 and arranged to engage the ends of a slot 43 in sleeve 39 to limit downward and upward movements of the latter, pin 42 engaging the lower end of slot 43 when opening 40 is out of registration with the upper end of passage 38 and engaging the upper end of slot 43 when opening 40 is in full registration with the upper end of passage 38. A head 44 may be threaded into the upper end of sleeve 39 to engage with the 90 95 100 105 110 115 120 125 130

adjacent lower end of float 35 upon downward movement of the latter to cause opening of valve 36 against the action of spring 41. Valve 36, of course, may be of any other 5 suitable construction.

From the foregoing it will be seen that an improved single chamber pump has been provided wherein the actuating mechanism for the fluid inlet and exhaust valves is simple 10 in construction and operation and is capable of continuous operation over a relatively long period of time without the necessity of replacement or readjustment of any of the parts.

15 Although but one embodiment of the invention has been shown and described, of course various changes may be made in the size, shape and arrangement of the parts without departing from the spirit of the invention or the scope of the claims.

The invention claimed is:

1. In a pump of the character described, the combination with a pump chamber and the fluid inlet and exhaust valves thereof, of 25 a lever connecting said valves for simultaneous operation, a float associated with said lever for operating the same at high level to cause closing of the fluid exhaust valve and opening of the fluid inlet valve, a second lever mounted in the pump chamber and arranged for engagement with said first-mentioned lever to impart initial opening movement to the exhaust valve and simultaneous closing movement to the inlet valve while permitting said float to complete said last-mentioned movements of the valves by its own weight, a second float for causing operative movement of said second lever at low level condition in the pumping chamber, and means operable at low level condition in said chamber for augmenting the action of said second float.

30 2. In a pump of the character described, the combination with a pump chamber and the fluid inlet and exhaust valves thereof, of a lever connecting said valves for simultaneous operation, a float associated with said lever for operating the same at high level to cause closing of the fluid exhaust valve and opening of the fluid inlet valve, a second lever mounted in the pump chamber and arranged for engagement with said first-mentioned lever to impart initial opening movement to the exhaust valve and simultaneous closing movement to the inlet valve while permitting said float to complete said last-mentioned movements of the valves by its own weight, and a second float for causing operative movement of said second lever at low level condition in the pumping 40 chamber.

35 2. In a pump of the character described, a pumping chamber having water inlet and outlet ports and fluid inlet and exhaust ports, valves for said ports, the fluid exhaust valve being arranged to close with the pressure in said chamber, means connecting the fluid exhaust and inlet valves for causing simultaneous opening and closing movements of the latter respectively and simultaneous reverse 45 movements of the same respectively, a lever arranged in said chamber above said means and pivotally supported at one of its ends, a buoyant member connected to the other end of said lever for causing downward pivotal

50 movement thereof under low level condition in said chamber, and a second float associated with said means for causing said reverse movements of the fluid valves under high level condition in said chamber while 55 permitting the fluid exhaust and inlet valves to remain closed and open respectively by virtue of the pressure in the pumping chamber acting on the fluid exhaust valve, said lever being arranged for engagement at a

60 point intermediate its ends and upon said 65 downward movement thereof with said means for initiating said first-named movements of the fluid valves against the pressure in said chamber while permitting continuation and completion of said movements by virtue of subsequent downward movement of said second float under the action of gravity.

3. In a pump of the character described, the combination with a pump chamber and the fluid inlet and exhaust valves thereof, of a lever connecting said valves for simultaneous operation, a float associated with said lever for operating the same at high level to cause closing of the fluid exhaust valve and opening of the fluid inlet valve, a second lever mounted in the pump chamber and arranged for engagement with said first-mentioned lever to impart initial opening movement to the exhaust valve and simultaneous closing movement to the inlet valve while permitting said float to complete said last-mentioned movements of the valves by its own weight, a second float for causing operative movement of said second lever at low level condition in the pumping chamber, and means operable at low level condition in said chamber for augmenting the action of said second float.

4. In a pump of the character described, the combination with a pump chamber and the fluid inlet and exhaust valves thereof, of a lever connecting said valves for simultaneous operation, a float associated with said lever for operating the same at high level to cause closing of the fluid exhaust valve and opening of the fluid inlet valve, a second lever mounted in the pump chamber and arranged for engagement with said first-mentioned lever to impart opening movement to the exhaust valve and simultaneous closing movement to the inlet valve while permitting said float to complete said last-mentioned movement of the valves by its own weight, a relief valve arranged below the low water line in said chamber and providing an auxiliary water outlet therefor, said relief valve being operable to open said outlet at substantially the same instant at which said second float begins to perform its said function, and means for closing said relief valve and for holding the latter closed during discharge of water from said chamber.

5. In a pump of the character described, the combination with a pump chamber and the fluid exhaust valve thereof, the latter being arranged to close with the pressure in the pumping chamber, of a member associated with said valve and adapted to act as a float under high level condition in said chamber to cause closing of said valve and as a weight under low level condition in said chamber tending to urge said valve from its seat, means responsive to low level condition in said chamber for initiating movement

115

120

125

130

of said valve away from its seat while permitting continuation and completion of said movement by virtue of the weight action of said member, means operable by said means for providing an auxiliary water outlet for said chamber when the water level in the latter is substantially at its lowermost point, and means for returning said last-named means to and for holding the same in closed position during discharge of water from said chamber.

6. In a single cylinder pneumatic pump, the combination with a pump chamber and the interconnected air exhaust and inlet valves and the float for actuating the latter in one direction, of a second float, mechanical means connected thereto and operated thereby for initially actuating said valves in the reverse direction, and a relief valve operable by said second float at low level condition in the pump chamber for providing an auxiliary water outlet therefor, said float permitting said relief valve to close during filling of said chamber.

25 7. In witness whereof, I hereto affix my signature.
